DESIGN FOR A COMBINED ASHTRAY SUPPORT AND CONTAINER FOR CIGARETTES OR LIKE ARTICLES

Isaac Mershon, Brooklyn, N. Y.

Application December 14, 1938, Serial No. 81,773

Term of patent 3½ years

To all whom it may concern:

Be it known that I, Isaac Mershon, a citizen of the United States and resident of the Borough of Brooklyn, in the county of Kings, city and State of New York, have invented a new, original, and ornamental Design for a Combined Ashtray Support and Container for Cigarettes or Like Articles, of which the following is a specification, reference being had to the accompanying drawing, forming part thereof.

Fig. 1 is a top plan view of a combined ashtray support and container for cigarettes or like articles, showing my new design.

Fig. 2 is a front elevation of the same.

I claim:

The ornamental design for a combined ashtray support and container for cigarettes or like articles, as shown.

ISAAC MERSHON.
